UNITED STATES PATENT OFFICE.

BENJAMIN A. EVANS, OF AKRON, OHIO, ASSIGNOR TO THE B. F. GOODRICH COMPANY, OF NEW YORK, N. Y., A CORPORATION OF NEW YORK.

APPARATUS FOR COATING STRIP MATERIAL.

Application filed January 22, 1925. Serial No. 3,953.

This invention relates to methods and apparatus for applying rubber cement or the like to strip material such as the fabric strips used in overshoes of the hookless-
fastener type as anchorages or stringers for respective series of jaw members, wherein the jaw members on the stringers of a pair are adapted to be intercalated and engaged with each other in succession by the movement of a slide mounted upon the two stringers in common, and to be disengaged from each other successively by movement of the slide in the opposite direction.

To adapt the stringers to become firmly united during vulcanization with the flies of the overshoe in which they are incorporated it is desirable that the stringers or fabric strips be thoroughly rubberized except along their adjacent edges, upon which the jaw members are mounted, and such rubberizing can best be done by an application of rubber cement after the jaw members and slide have been mounted thereon, the two stringers of the pair joined at their ends which are to be at the lower part of the assembly in the overshoe, and the two series of jaw members intercalated and engaged with each other by movement of the slide to the opposite end of the assembly. It is important that the cement be uniformly applied to all parts of the stringers which are to overlap or extend into the margins of the flies of the shoe, without application of cement to the jaw members or the slide, and prior to my invention, so far as I am aware, this was accomplished by placing a shield or stencil over the jaw members and slide and applying the cement to the exposed portions of the stringers by means of a brush, manipulated by hand.

My chief object is to provide an improved machine and improved procedure adapted to save time and labor in applying rubber cement or the like to articles such as the stringers or anchorage strips described. Further objects are to avoid waste of the material applied and to provide for accurate and uniform application of the material, so as to obtain a better product.

50 Of the accompanying drawings:

Fig. 1 is a front elevation of a machine embodying my invention in its preferred form, a cement tank constituting a part thereof being shown in section.

Fig. 2 is a fragmentary front elevation, 55 partly in section, of a pair of cementing rolls constituting parts of said machine.

Fig. 3 is a perspective view of scraper devices for preventing the rolls from carrying excessive amounts of cement, one of the 60 rolls being shown in dot and dash lines, in its relation to said scraper devices.

Fig. 4 is a middle, vertical section of the machine, on line 4—4 of Fig. 1.

Fig. 5 is a horizontal section of the ma- 65 chine, on line 5—5 of Fig. 1.

Referring to the drawings, the machine comprises a cement tank 10 provided with legs 11, 11, and a cover 12 for preventing excessive evaporation of solvent from rubber cement 13 contained in the tank. Said cover is cut away to accommodate, with but little clearance, the cement-transferring portions of the machine. Resting upon the floor of the tank and adapted to be readily removed therefrom is a metal block 14, upon which are mounted two pairs of guide posts, 15, 15 and 16, 16, for the journal blocks, such as 17, 17, of a pair of cementing rolls 18, 19, the lower one of which, 19, has 70 its lower portion extending into the cement 13, and is adapted, by turning of the rolls without work therein, to apply cement to the upper roll. For securing the guide-post assembly in upright position in the tank a 75 bracket 16^a is secured to one of the guide posts 16 and has a forked outer end adapted to straddle the upper margin of a wall of the tank, one of the forks being provided with a thumb screw 16^b adapted to be tightened 80 against the said wall to clamp the bracket 85 in place.

The journal blocks of the lower roll, 19, mounted between the guide posts, are supported by blocks, of which one is shown at 90 20, Fig. 4, mounted between the guide posts and resting upon the foundation block 14, and the journal blocks of the upper roll, mounted between the guide posts, are urged downward, to provide yielding pressure between the rolls, by compression springs such as the one shown at 21, Fig. 4, interposed 100 between the respective journal blocks and a bridge plate 22 screwed to the tops of the four guide posts, said springs being mounted 105 upon respective studs such as the one shown at 23, Fig. 4, projecting downward from said bridge plate.

Each of the cementing rolls is waisted or formed with a medial, circumferential groove, 18^a or 19^a, for the free passage of the jaw members, 24, 24, and slide, 25, of the 5 fastener assembly, 26, said jaw members constituting in effect a medial rib thereon, while the rolls' circumferential zones adjacent said grooves are adapted yieldingly to embrace the stringers, 27, 27, of the fastener 10 assembly, and feed the latter through the device while applying cement to both faces of the stringers. Said zones are knurled, preferably being formed with knurling elements of pyramidal form, as shown clearly 15 at 28, 28, Fig. 2, the points of said elements preferably lying slightly within the radial limits of the adjacent cylindrical faces of the roll. The knurling is adapted to carry a relatively large quantity of cement and at the same time to avoid slippage 20 of the cement-lubricated fabric strips.

Between each knurled zone and the medial groove each roll is preferably formed with a flange 29 having a narrow cylindrical surface 25 30 of larger diameter than that of the knurling, so that the flanges of each pair will bear against each other when the work is not in place between them, which results in the flange face 30 of the upper roll, which 30 operates on the outer face of the fastener, being kept substantially free of cement. The said flanges are adapted to press more firmly upon the work than the knurled portions, and thus to serve as a sort of dam to 35 prevent extrusion of cement from the knurled zones onto the jaw members 24 or the portions of the stringers immediately adjacent thereto.

The two rolls are adapted to be driven by 40 a hand crank 31 secured upon the shaft of the lower roll and a pair of intermeshed gears 32, 32 secured upon the shafts of the two rolls respectively.

For guiding the fastener assembly 26 45 between the rolls, a table or bracket 33 is mounted upon a bridge structure 34 connecting one of the guide posts 15 with the opposite post 16, said bridge structure being secured to said posts by brackets 35, 35, and 50 the work guiding bracket 33 is formed on its upper face with a longitudinal groove 36 to accommodate and guide to the rolls the jaw members 24 and slide 25 of the fastener assembly, and with a tongue portion 33^a 55 whose upper face is an extension of the floor of said groove, said tongue portion extending between the cementing rolls, past the nip thereof, at the position of their circumferential grooves 18^a, 19^a.

To prevent the fastener assembly from adhering to and thus following the upper roll, as it passes from the nip of the rolls, a guard 37, in the form of a curved bar, is secured to the bridge plate 22 and has a free end portion extending into the groove 18^a

of the upper roll, adjacent the nip, in position to dislodge the work from the upper roll. The tongue 33^a of the guide 33 is adapted to prevent the work from following the lower roll downward from the nip. 70

The bridge structure 34 comprises a lower plate 38, secured to the adjacent guide posts by the brackets 35, and an upper plate 39 held spaced from said lower plate by a scraper 40 secured to the lower plate by 75 screws 40^a, 40^a (Fig. 4), said scraper extending into the groove 19^a of the lower roll, to scrape cement from the walls and floor of said groove, and by a pair of scrapers 41, 41 secured to the lower plate by screws 41^a, 41^a, 41^b, 41^d, and extending radially inward along the end faces of the roll 19 to scrape cement from said end faces. The screws 41^b extend through the upper plate 39 as well as the scrapers 41 and the 80 lower plate 38, but the construction is such that the upper plate 39 and parts carried thereby may be conveniently removed for cleaning cement therefrom, by removing said screws 41^b and screws 42, 42 which are mounted only in the upper plate 39 and the scrapers 41, while the screws 41^a hold said scrapers in place on the lower plate. 85

Secured on the upper plate 39 are two screw-apertured blocks 43, 43 in each of 90 which is mounted a thumb-screw 44 having its inner end swiveled in a flange 45 projecting upward from a scraper 46, each of the said scrapers being slidably mounted in a guide-way defined by the plates 38 and 39 and the bases of the fixed scrapers 40, 41, so that the scrapers 46 may be adjusted by said thumb-screws respectively to scrape excess cement from the knurled and cylindrical faces of the lower roll 19. The scraper 95 assembly just described is adapted for ready disassembly of its parts for cleaning cement therefrom when they become fouled, so that the harmful effects of dried cement upon their operation may be avoided. 100

For scraping excess cement from the upper roll, 18, and returning it to the tank 10, an L-shaped chute 47 is mounted upon a pair of scrapers 48, 48 adapted to scrape the end faces of the said upper roll 18 and upon a scraper 49 adapted to scrape cement from the walls and floor of the medial groove 18^a of said roll, said scrapers 48 and 49 at their bases serving as spacers between the chute 47 and a lower plate 50 connecting the outer ends of a pair of brackets 51, 51, projecting from the adjacent corner posts 15, 16. Slidably mounted in guide-ways defined by the chute 47 and the bases of the scrapers 48, 48 are scrapers 52, 52 adapted to scrape excess cement from the working faces of the roll 18, each of said scrapers having projecting downward therefrom a lug 53 in which is swiveled the end of a thumb-screw 54 screw-threaded through 115 120 125 130

a lug 55 projecting downward from the plate 50, for adjusting the scrapers 52 to determine the amount of cement to be carried to the work by the roll. The floor of the chute 47 and also the several scrapers, fitting against the under face thereof, slope downward and away from the roll, so that cement scraped from the roll will flow away from the roll and, through the vertical portion of the chute, back into the tank 10.

Secured to the under face of the plate 50 is a bracket 56 on the outer end of which is pivoted at 57 a lever 58 having a hold-down roller 59 journaled on its inner end and adapted to bear upon the medial zone of the work to hold the latter down against the guide bracket 33, the outer end of said lever being connected to the chute 47 by a pull spring 60.

In the operation of the device, the parts being mounted as described and the tank 10 being filled to a proper level with cement, the cementing rolls are first rotated without any work between them, whereby the upper roll as well as the lower one is charged with cement. A fastener assembly 26 is then passed through the device, its margins being engaged by the surfaces of the rolls 18, 19, adjacent the grooves 18^a, 19^a, and receiving cement therefrom. The operation as described is repeated upon successive fastener assemblies, the rolls being driven without work between them before each piece of work is fed through, or at sufficiently frequent intervals to keep the upper roll sufficiently charged with cement. Excess cement from the rolls flows back into the tank 10, and the cover thereof, closely fitting about the cementing mechanism, keeps the cement in good condition by preventing excessive evaporation of solvent.

All parts of the apparatus may be readily disassembled from each other for cleaning, which is of great advantage in the use of quick-drying adhesives such as rubber cement. Other advantages of the apparatus will be readily understood in view of the above statement of objects.

Modifications are possible within the scope of the invention, and I do not wholly limit my claims to the specific construction or the exact procedure described.

I claim:

1. A device for applying a coating to an elongated, medially ribbed article, said device comprising two pairs of axially spaced-apart roller means adapted to engage the side margins only of the article and to feed the same past a coating position, and means adapted to support the article and to guide it to the said roller means by engagement with its medial rib.

2. A device for applying a coating to an elongated, medially ribbed article, said device comprising two pairs of axially spaced-

apart roller means adapted to engage the side margins only of the article and to feed the same past a coating position, means adapted to support the article and to guide it to the said roller means by engagement with its medial rib, and a yieldingly urged presser roller for holding the article against the said supporting and guiding means. 70

3. A device for applying a coating to an elongated, medially ribbed article, said device comprising two pairs of axially spaced-apart roller means adapted to engage the side margins only of the article and to feed the same past a coating position, means adapted to support the article and to guide it to the said roller means by engagement with its medial rib, and means for applying coating material to the work-engaging faces of the said roller means. 75

4. A device for applying a coating to an elongated article, said device comprising two pairs of axially spaced-apart roller means adapted to engage the side margins only of the article and to feed the same past a coating position, and means for applying coating material to the work-engaging faces of the said roller means, said faces comprising smooth, circumferential zones adapted to engage the article relatively close to its medial portion and knurled, circumferential zones adapted to apply coating material to portions of the article relatively remote from its medial portion. 80

5. A device for applying a coating to an elongated, medially ribbed article, said device comprising two pairs of axially spaced-apart roller means adapted to engage the side margins only of the article to feed the same and apply coating material thereto, means for applying coating material to the work-engaging faces of said roller means, and a guiding and supporting member extending through the space between the two pairs of roller means, from one side of their nip to the other, said member being adapted to guide the article to the roller means by engagement with its medial rib and to separate the article from members of the roller means as it emerges from the nip thereof. 100

6. A coating device comprising a roll formed with a roughened, circumferential, material-carrying zone and with a circumferential flange adjacent thereto, said flange being of greater diameter than the said roughened zone and adapted to act as a guard against lateral flow of coating material on the work from said roughened zone as the said roll rotates in contact with the work. 110

7. A coating device comprising a pair of rolls formed with opposed, circumferential, material-carrying zones and with mating, outstanding, circumferential zones of smooth, cylindrica' surface, means yield- 120

ingly urging one of the said rolls toward the other, and means for applying coating material to one of said rolls, the outstanding, cylindrical zones of said rolls being adapted to bear against each other when the device is empty of work, to maintain one of them substantially free of coating material when

the rolls are turned to transfer coating material from the material-carrying zone of one roll to that of the other.

10

In witness whereof I have hereunto set my hand this 17th day of January, 1925.

BENJAMIN A. EVANS.
